United States Patent Office

Des. 185,310
Patented May 26, 1959

185,310

ASH TRAY

Doak Norwood, Chicago, Ill.

Application August 11, 1958, Serial No. 52,155

Term of patent 14 years

(Cl. D85—2)

Fig. 1 is a front perspective view of an ash tray, showing my new design; and

Fig. 2 is a rear perspective view thereof.

The broken line showing of a cigarette package in Fig. 1 is for illustrative purposes only.

I claim:

The ornamental design for an ash tray, as shown and described.
